(57) **CLAIM**

The ornamental design for a headset, as shown and described.

DESCRIPTION

FIG. 1 is a rear and right perspective view of a headset, showing my design.

FIG. 2 is a front and top perspective view the headset in FIG. 1.

FIG. 3 is a front view of the headset in FIG. 1.

FIG. 4 is a rear view of the headset in FIG. 1.

FIG. 5 is a left side view of the headset in FIG. 1.

FIG. 6 is a right side view of the headset in FIG. 1.

FIG. 7 is a top view of the headset in FIG. 1; and,

FIG. 8 is a bottom view of the headset in FIG. 1.

The broken lines shown in the drawings are included for the purpose of illustrating portions of the headset that form no part of the claimed design.

1 Claim, 8 Drawing Sheets
